ELECTRIC CIRCUIT CONTROLLING
APPLIANCE

Joseph Sachs, West Hartford, Conn.

Application July 17, 1934, Serial No. 735,565

3 Claims. (Cl. 200—16)

This invention relates particularly to an appliance of the general character disclosed in my copending application for Electric circuit controlling appliances, Serial No. 659,922, filed March 7, 1933. The appliance shown in the said application includes two stationary opposed switch contacts and a switching member rectilinearly movable between them, and it also includes a removable insulating retainer plate at the front of the switching member for normally holding the said switching member in place and guiding it. Formed integrally with the retainer plate are rearward projections located to provide opposite insulating walls closely adjacent the paths of movement of the switching member so as to minimize arcing.

In accordance with the present invention I provide removable insulating blocks closely adjacent the paths of movement of the movable contact, but these blocks are entirely separate from the front retaining plate although they are normally held in place thereby. By providing separate insulating blocks various important advantages are obtained, as will be apparent from the following specification and claims.

In the drawings I have shown the embodiment of the invention which I now deem preferable, but it will be understood that the drawings are intended for illustrative purposes only and are not to be construed as defining or limiting the scope of the invention, the claims forming a part of this specification being relied upon for that purpose.

Of the drawings:

Fig. 1 is a fragmentary front view of a circuit controlling appliance embodying the invention, portions of the enclosing box being broken away and the front cover thereof being entirely omitted.

Fig. 2 is a combined elevational and sectional view taken along the line 2—2 of Fig. 1.

Fig. 3 is a perspective view showing parts of one of the switching units separated from each other.

In the drawings I have shown a two-pole switch, but inasmuch as the parts for the two poles are identical in construction, except for reversal of arrangement, it will be sufficient to describe only one set of parts, as for instance, those at the right.

1 represents as an entirety the enclosing box which is or may be of any usual or preferred construction. It has a rear wall 1^a and side walls 1^b, 1^c. Mounted in the side walls is a cranked operating spindle 2 of conventional form having an exterior handle 2^a.

Secured to a rear supporting wall, which may be and preferably is the aforesaid rear wall 1^a of the enclosing box, is an insulating means or block 3 for supporting the stationary switch contacts. Preferably there is a separate block 3 for each leg of the circuit, but as to this I do not limit myself. The block 3 is held in place on the wall 1^a by means of screws 4, 4. Projecting forward from the block 3 are two opposed stationary switch contacts 5 and 6, these contacts being perpendicular to the block 3 and having at their inner sides parallel contact faces. The contacts 5 and 6 are held in place respectively by means of screws 7 and 8. Electrically connected with the contact 5 is a wire connecting lug 9. Preferably a fuse contact 10 is directly supported upon and electrically connected with the front portion of the contact 6. As shown the contact 10 is adapted for receiving a fuse of the knife blade type, but the invention is not so limited.

For making and breaking the circuit between the stationary switch contacts 5 and 6 I provide a switching member which is rectilinearly movable between them parallelly with the rear supporting wall 1^a. The switching member comprises a thin flat insulating element or plate 11 which supports or carries a movable contact 12 having its outer contact faces spaced apart sufficiently to engage the inner contact faces of the two stationary contacts 5 and 6. The switching member is guided in part at the rear by the insulating block 3 and it is additionally guided at the rear by means of metallic plates 13, 13 which are secured to it and which project rearward into guiding engagement with the rear wall 1^a of the box. Pins 14, 14 are provided on the block 3 for engaging the insulating plate 11 to limit lateral movement thereof. The pins 14, 14 are spaced apart sufficiently to allow limited lateral movement of the switching member, thus enabling the said member to adjust itself laterally so as to provide the most effective contact between the stationary contacts and the movable contact.

The insulating plate 11 is provided at 11^a with a slot adapted to receive the crank portion of the spindle 2. By means of the cranked spindle the switching member can be moved rectilinearly. With the parts in the position shown in Fig. 1, the contact 12 of the switching member is disengaged from the stationary contacts 5 and 6, but by moving the handle 2^a of the spindle upward the switching member can be moved downward so as to bring the movable contact 12 into

contacting engagement with the stationary contacts 5 and 6.

Two stationary insulating blocks 15, 15 are provided having walls which are closely adjacent the paths of movement of the contact faces of the movable contact 12. These blocks are separate from the insulating block 3 and are readily removable therefrom, but they are preferably connected with the said block 3 so as to be supported thereby. As shown, each block 15 is provided with a rearward extending pin 16 adapted to enter a suitable hole 17 in the block 3. The pins 16, 16 normally serve to hold the blocks 15, 15 in position, but the said pins leave the said blocks free to be removed in the forward direction.

Preferably the insulating member 11-12 carries a movable arc resisting structure 18 of the type set forth in my copending application for Electric switches, Serial No. 616,407 filed June 20, 1932, on which has been issued Patent No. 1,993,416 dated March 5, 1935. The insulating plate 11 is provided with a rectangular hole which permits the movable contact 12 to be initially bent to shape and then assembled with the plate 11. The block 18 is formed of insulating material, preferably of a refractory character, and this block 18 is inserted in the hole in the plate 11 in such a manner as to hold the contact 12 in position. The block 18 is suitably held in place in the said hole, as for instance by means of nails 19, 19 driven horizontally into it from the edges of the plate 11. The insulating arc resisting block 18 is preferably considerably thicker than the plate 11 and the said block 18 cooperates directly with the stationary blocks 15, 15 to provide a restricted passage which tends to pinch out or at least minimize the action of any arcs that may be formed between the stationary contacts 5 and 6 and the movable contact 12.

40 At the front of the switching member 11-12 and at the front of the insulating blocks 15, 15 is mounted a block or plate 20 which serves as a retainer. This block may be mounted in various ways, but as shown there is provided a metallic bracket 21 secured to the stationary contact 6, and screws 22, 22 extend forward through the retainer 20 and engage threaded holes in the bracket 21. When the retainer 20 is in place and held by the screws 22, 22 as described, it engages the blocks 15, 15 to prevent forward removal thereof. The forward retainer 20 also serves to hold the switching member and to serve as a front guide therefor. The said retainer is provided with a slot 20* into which the edge portion of the insulating plate 11 projects, but the slot is somewhat wider than the said plate 11 so as to permit limited lateral movement for the purpose already set forth. It will be observed that with the retainer 20 in place the switching member and the insulating blocks 15, 15 are held against removal in the forward direction, but that upon removal of the retainer 20 the said switching member and the said blocks are freely removable in the forward direction.

65 The fuse contact 10 carried by the switch contact 6 is one of a pair of fuse contacts and the other contact of the pair may be mounted in any suitable manner. As shown there is a companion contact 23 mounted on a small insulating block 24. The block 24 is in turn mounted on a metallic bracket 25 secured to the rear wall 1* of the cabinet. When there are two pairs of fuses and two blocks 24, 24 as shown, both blocks may be mounted on the same metallic bracket 25.

75 Preferably in order to tie together the two

switching units and in order to provide an additional front guide for the switching members there is a transverse insulating plate 26. This plate 26 is supported by means of downward extensions 21*, 21* on the before-mentioned brackets 21, 21 and is secured to the said bracket extensions by means of screws 27. As already stated, the plate 26 serves as an additional front guide for the switching members and the said plate may be provided with rearward projecting pins 28, 28 for limiting lateral movement of the said switching members. It will be understood that the tie plate 26, while preferred, is not essential and may be omitted if desired. When the tie plate is omitted the said retainers 20, 20 serve as the sole front guiding means for the switching members.

What I claim is:

1. In an appliance of the type disclosed, the combination of a rear insulating supporting means, two stationary opposed switch contacts on the supporting means and perpendicular thereto, a switching member rectilinearly movable between the stationary switch contacts and comprising a movable contact with oppositely disposed faces adapted to engage or disengage the said stationary contacts, two removable insulating blocks located to provide opposite insulating walls closely adjacent the paths of movement of the faces of the movable contact, and an insulating retainer separate from the said insulating blocks and located at the front thereof and at the front of the switching member, the said retainer normally serving to hold the insulating blocks in place and also normally serving as a front guide for the switching member and the said retainer being removable so as to permit removal of the said blocks or of the said switching member.

2. In an appliance of the type disclosed, the combination of a rear insulating supporting means, two stationary opposed switch contacts on the supporting means and perpendicular thereto, a switching member rectilinearly movable between the stationary switch contacts and comprising a movable contact with oppositely disposed faces adapted to engage or disengage the said stationary contacts, two insulating blocks separate from the supporting means and located to provide opposite insulating walls closely adjacent the paths of movement of the faces of the movable contact, means for normally supporting the blocks on the rear supporting means but permitting free removal in the forward direction, and an insulating retainer separate from the said insulating blocks and located at the front thereof and at the front of the switch member, the said retainer normally serving to hold the insulating blocks in place and also normally serving as a front guide for the switching member and the said retainer being removable so as to permit removal of the said blocks or of the said switching member in the forward direction.

3. In a fused switch, the combination of a rear insulating supporting means, two stationary opposed switch contacts on the supporting means and perpendicular thereto, a switching member rectilinearly movable between the stationary switch contacts and comprising a movable contact with oppositely disposed faces adapted to engage or disengage the said stationary contacts, a pair of coating fuse receiving contacts one of which is fixedly mounted on the forward portion of one of the said switch contacts, two removable

insulating blocks separate from the supporting means and located to provide opposite insulating walls closely adjacent the paths of movement of the faces of the movable contact, and an insulating retainer located at the front of the switching member and at the front of the said insulating blocks and directly behind the axis of a fuse in the said fuse contacts, the said retainer normally serving to hold the said insulating blocks in place and also normally serving as a front guide for the switching member and the said retainer being removable so as to permit removal of the switching member or of the said blocks without disturbing the mounting of the said fuse contact on the said switch contact. 5

JOSEPH SACHS.
